METHOD AND MEANS FOR SHAPING SHOE
UPPER MATERIALS TO THE CONTOUR OF
A LASTEuclid I. La Chapelle, Brockton, Mass., assignor
to United Shoe Machinery Corporation, Paterson, N. J., a corporation of New Jersey

Application February 21, 1938, Serial No. 191,632

20 Claims. (Cl. 12—7)

This invention relates to methods of and means for shaping shoe upper materials, and is herein illustrated by reference to the shaping of the heel-end portion of the upper materials to the contour of the heel end of a last prior to the heel seat lasting operation.

The invention in one aspect provides a novel method whereby shoe upper materials (hereinafter sometimes referred to as the upper) at the opposite sides of the heel end of the last are tensioned heightwise of the last toward its bottom face and are then wiped toward the bottom face of the last while pressure and heat are applied to the upper materials to shape them to the contour of the last. In accordance with the illustrated practice the upper materials at the opposite sides of the heel end of the last are worked heightwise of the last toward its bottom face by the use of rubber faced wiping tools, after which the upper materials are wiped toward the bottom face of the last by the use of unheated metal-faced wiping tools arranged to press them more firmly against the opposite side faces of the last and are then again wiped toward the bottom face of the last by the use of heated metal-faced tools, the heat tending to shrink the upper materials and to set them in shaped condition close to the edge of the bottom face of the last. The shoe is thus prepared better for the subsequent heel seat lasting operation, the shaping of the upper materials to the contour of the heel end of the last, in the manner above described, tending to prevent the formation of wrinkles therein close to the edge of the last bottom as the margins of the upper materials are wiped inwardly over the bottom of the last by the wipers of the heel seat lasting machine. It is further contemplated that in operating upon shoes the outer layer of the upper materials of which is made of patent leather a thin coating of vaseline may be applied to the patent leather in order to prevent any danger of damaging the finish on the outer layer as the heat is applied to assist in setting the upper materials in shaped condition.

In a further aspect the invention provides a novel machine organization particularly adapted for shaping the heel-end portion of shoe upper materials to the contour of the heel end of the last in accordance with the above-mentioned method. For the purpose in view the construction shown comprises a plurality of upper shaping or wiping devices, and means for effecting relative movement of these devices and the shoe to wipe the upper at the opposite sides of the

heel end of the last repeatedly heightwise of the last toward its bottom face. The machine herein shown is provided with means for supporting a last and shoe having its heel end unlasted, and with means for moving the wiping devices in succession heightwise of the last toward its bottom face, one of the wiping devices having its upper engaging faces formed of rubber to increase its frictional pull on the upper. In order to assist in setting the upper in shaped condition and in eliminating wrinkles, there is provided in the machine herein shown, in accordance with a further feature, means for maintaining another one of the wiping devices in a heated condition to apply heat to the upper. There is further provided, in accordance with still another feature of the invention, a device that is movable with the wiping devices for applying a lubricant to the upper prior to the action of the heated wiping device on the upper, and means for rendering this lubricant-applying device operative or inoperative at will. In the construction shown, each upper shaping or wiping device comprises a pair of holders one at each side of the shoe, the holders of each device being carried at the outer ends of a pair of parallel arms. Yieldingly mounted in each holder are a plurality of upper-engaging members, the upper-engaging members at the opposite sides of the shoe having their upper-engaging faces shaped to conform substantially to the opposite edge curvatures of the bottom face of the heel-end portion of the last. As the upper-shaping devices are moved in succession heightwise of the shoe by the different pairs of parallel arms the upper-engaging members of each device act on the upper to press it against the opposite side faces of the last and to wipe it heightwise of the last toward its bottom face. Preferably and as shown, the device for applying a lubricant to the upper is substantially a duplicate of the upper-shaping devices except that its upper-engaging members are faced with felt to apply the lubricant, and the pair of parallel arms carrying this device are formed in two parts relatively adjustable to position the holders of the device either in operative or inoperative relation to each other and the shoe.

The above and other features of the invention, including various novel details of construction and combinations of parts and also the novel method aspects of the invention will now be more particularly set forth by reference to the accompanying drawings and pointed out in the claims.

In the drawings.

Fig. 1 is a view in left-hand side elevation of a machine adapted for use in carrying out the novel method and embodying novel features of the invention;

Fig. 2 is a view partly in plan and partly in section of the machine shown in Fig. 1 with one of the upper shaping devices in engagement with the shoe; and

Fig. 3 is a detailed plan view of a holder of one of the upper shaping devices with the cover plate removed to show more clearly the construction of the upper-engaging members.

The illustrated machine is provided with upper-shaping devices, hereinafter more particularly referred to, for wiping the heel-end portions of shoe upper materials at the opposite sides of the last heightwise of the last toward its bottom face repeatedly while applying pressure and heat to the upper materials to shape them to the contour of the heel-end portion of the last prior to the heel-seat lasting operation. The upper-shaping devices 10, 12 and 14 (Fig. 1) are carried respectively on the outer ends of different pairs of parallel arms 16, 18 and 20, the arms carrying the several tools that operate at the same side of the shoe having a common hub portion pinned to a shaft 22. The shaft 22 is supported in bearings at the upper ends of spaced arms 26, 28 (Fig. 2) that extend upwardly from the base 30 of the machine. As illustrated, the bearings for the shaft 22 are formed partly in the arms 26, 28 and partly in caps 32, one of which is shown in Fig. 1, that are secured to the arms by screws 34. The right-hand end portion of the shaft 22 (Fig. 2) is supported by a bearing 36 projecting upwardly from the base 30, and surrounding the shaft 22 between a finished surface 38 on the arm 28 and a collar 40 pinned to the shaft is a bushing 42 upon which there is rotatably mounted a worm wheel 44 which is held against endwise movement on the bushing 42 by means of the collar 40 and a ball thrust bearing 46 between the worm wheel and the finished surface 38 on the arm 28. Engaging the teeth of the worm wheel 44 is a worm 48 (Fig. 1) fast to a forwardly and rearwardly extending shaft 50 mounted in suitable bearings on the base 30 and having fast to its outer end a pulley 52 continuously driven by means of a belt (not herein shown). The worm wheel 44 is provided with an internal friction clutch face 54 (Fig. 2) arranged to cooperate with a clutch member 56 slidingly mounted for lengthwise movement on the shaft 22 and which is arranged to engage a stationary brake surface 58 when it is not in engagement with the clutch face 54. The clutch member 56 is connected to the shaft 22 by a key 60 which projects into a lengthwise slot 62 formed in the clutch member. Surrounding the shaft 22 between a collar 64 pinned to the shaft and the hub of the clutch member is a spring 66 which tends to move the clutch member 56 into engagement with the clutch face 54. The hub of the clutch member is provided with an annular groove 68 into which extends a roll 70 carried by a hand lever 72 pivotally connected at 74 to a boss 76 formed on the bearing 36. A cam 78 on the hub of the clutch member 56 acts by engagement with the roll 70 to hold the clutch member 56 against the resistance of the spring 66 in engagement with the stationary brake surface 58. It will be evident that the operator may trip the clutch to start the machine by swinging the hand lever 72 in a direction to move the roll 70 out of engagement with

the cam 78, the spring 66 then acting to move the clutch member 56 into engagement with the clutch face 54 on the continuously driven worm wheel 44. A spring 80 (Fig. 1) connected at one end to the hand lever 72 and at the other end to the base 30 acts to swing the hand lever, when released by the operator, in the direction to move the roll 70 into position to be engaged by the cam 78 and to cause the clutch member 56 to be moved into engagement with the brake surface 58 to stop the machine.

Each one of the upper-shaping devices 10, 12 and 14 comprises a pair of holders 82, the holders of each device being secured to the outer ends of their respective supporting arms each by a nut and washer 84 threaded on the end of a shank portion 85 that is formed on the holder and that projects through a bore in the arm. Mounted in each holder 82 are a plurality of upper-engaging members or blocks 86, herein illustrated as three in number (Fig. 3), the blocks in the holders at the opposite sides of the shoe having their upper-engaging faces curved to conform substantially to the opposite edge curvatures of the bottom face of the heel-end portion of the last. Each holder 82 is provided with a recess 88 to receive the blocks 86 which are held against movement heightwise of the shoe relatively to each other and to the holder by a cover plate 90 secured to the holder by screws 92. Formed on each block 86 is a shank portion 94 extending through an opening 96 in the holder and having pinned to its outer end a collar 98. Surrounding each shank portion 94 between a shoulder 100 on the block and the rear wall 102 of the recess 88 is a spring 104, the springs 104 tending normally to hold the blocks 86 in each holder in the positions shown in Fig. 3 with the collars 98 in engagement with the outer face 106 of the holder 82.

The machine is provided with a shoe support 40 or jack comprising a slide 108 which is vertically movable in guideways formed at the front of the base 30. Formed integral with the slide 108 is an upwardly extending post 110 on the upper end of which is slidably mounted for movements in directions lengthwise of the shoe a block 112 arranged to engage the top face of the heel-end portion of the last, the block 112 being provided with a spindle 114 arranged to extend into the spindle hole in the heel end of the last. For supporting the last and shoe against the upwardly directed pressure of the upper-shaping devices there is provided a holdown 116 for engaging the bottom face of the heel-end portion of the shoe. The holdown 116 is secured by screws 118 to an arm 120 (Fig. 2) that extends upwardly from the base 30 between the arms 26 and 28, the upper portion of the arm 120 being bored to receive the shaft 22. A spring 124 bearing at its lower end against a projection 126 on the base 30 and at its upper end against a shoulder formed within a recess in a projection 128 on the slide 108 tends to impart upward movement to the slide and to hold the last and shoe mounted on the spindle 114 and block 112 clamped against the holdown 116. For lowering the shoe support to permit a last and shoe to be removed from the spindle 114 and another shoe to be mounted thereon, there is pivotally connected to the base 30 at 130 a treadle 132 connected by a link 134 to the slide 108.

In the course of the operation of the machine the upper-shaping devices 10, 12 and 14 are moved successively, in that order, relatively to the shoe supporting means to wipe the upper materials at the opposite sides of the heel end 75

of the last heightwise of the last toward its bottom face. Preferably the holders 82 of each device are so located relatively to each other laterally of the shoe that the upper-engaging faces of the blocks 86 of each device are spaced apart to provide an opening that is narrower than the width of the bottom face of the heel-end portion of the smallest shoe to be operated upon so that as the shaping devices are moved relatively to the shoe to wipe the upper materials the blocks 86 yield laterally of the shoe relatively to one another and to their holders 82 against the resistance of the springs 104 and press the upper materials against the opposite side faces of the last. The upper-engaging faces of the blocks 86 of the shaping device 10 are formed of rubber to cause the device 10 as it is moved relatively to the shoe to tension the upper materials frictionally heightwise of the last, and the springs 20 104 of the shaping device 12 which is provided with metal-faced blocks 86 are of greater capacity than the springs 104 of the devices 10 and 14 so that more substantial pressure is applied to the upper materials laterally of the last as they are wiped toward its bottom face by the device 12. The machine is further provided with means for maintaining the blocks 86 of the shaping device 14 in a heated condition, the blocks 86 of this device also having metal upper-engaging faces. For this purpose there is mounted in a recess in the upper end of each arm 20 an electrical heating unit 136, one of which is shown in Fig. 1, and from each unit electrical conductors 138 lead to contact rings 140 fast to the arms 16, 18 and 20, insulating rings 142 being provided between the contact rings and the arms 16, 18 and 20. Engaging the contact rings 140 are brushes 145 mounted in the arm 120 and from the brushes electrical conductors mounted within a flexible cable 144 lead to a switch box 146 on the base 30 of the machine. From the arms 20 the heat is conducted through the holders 82 to the blocks 86.

In operating upon shoes the outer layer of the upper materials of which is made of patent leather it is desirable in order to avoid any danger of damaging the finish on the outer layer to apply a thin coating of vaseline to the patent leather before applying heat thereto to assist in setting the upper materials in shaped condition. For this purpose there is provided a device 148 which is substantially a duplicate of the upper-shaping devices 10, 12 and 14 except that the springs 104 of this device are comparatively light and the blocks 86 are faced with felt or other suitable material to which vaseline may be applied by the operator. The device 148 is carried on the outer ends of a pair of parallel arms 150 that project from the common hub portions of the parallel arms 16, 18 and 20 substantially opposite to the arms 16 and between the arms 18 and 20 (Fig. 1). Each arm 150 is formed in two parts pivotally connected together at 152. The outer portion 154 of each arm carries a spring-pressed plunger 156 arranged to enter either one of a pair of recesses 158, 160 formed in the inner portion of the arm. Secured to the upper end of each plunger 156 is a knurled knob 162 by means of which the operator may disengage the plungers from the inner portions of the arms and swing the outer portions of the arms relatively to the inner portions to move the holders of the device toward or away from each other to render the device either operative or inoperative as desired, the holders of the device 148 being positioned in

operative relation to each other and to a shoe mounted on the spindle 114 when the plungers 156 are in engagement with the inner portions of the arms 150 in the recesses 158, and out of operative relation to each other and the shoe when the plungers are in engagement with the inner portions of the arms in the recesses 160.

In the operation of the machine the operator, after depressing the treadle 132 to lower the shoe support, mounts a last and shoe on the spindle 10 114 and moves the block 112 and shoe either rearwardly or forwardly to position the shoe with the bottom face of its heel-end portion under the hold-down 116 and then releases the treadle 132 to permit the spring 124 to move the shoe support upwardly and to press the bottom of the shoe against the hold-down. It will be understood that before the shoe is presented to the machine it will have been previously lasted at least along the opposite sides of the shank portion of the 20 shoe. With the shoe clamped against the hold-down the operator swings the hand lever 72 in a direction to move the roll 70 out of engagement with the cam 78 to start the machine, whereupon the upper-shaping device 10 engages 25 the upper materials frictionally at the opposite sides of the last and tensions them heightwise of the last toward its bottom face, after which the upper materials are wiped heightwise of the last by the upper-shaping device 12, which acts to 30 press the upper materials more firmly against the opposite side faces of the heel-end portion of the last, and then by the heated shaping devices 14. It will be understood that the operator may render the device 148 operative to apply a 35 thin film of vaseline to the outer layer of the upper materials if desired in operating, for example, on shoes the outer layer of the upper materials of which is made of patent leather. It will be evident that as the heel-end portions of the upper materials are thus tensioned heightwise of the last toward its bottom face and are also wiped heightwise of the last and are pressed firmly against the opposite side faces of the last any wrinkles or other surface irregularities that may have been 40 formed in the upper materials are eliminated and the upper materials are shaped to conform substantially to the heightwise curvatures of the opposite lateral faces of the heel-end portion of the last, the heat applied to the upper materials by the shaping device 14 tending to shrink the upper materials and to set them in shaped condition with the marginal portions of the upper materials close to the edge of the bottom face of the last. This treatment of the upper materials contributes 45 to the production of a better lasted shoe since it tends to prevent the formation of wrinkles in the upper materials close to the edge of the last bottom in the subsequent heel seat lasting operation. Moreover, since the upper materials are 50 shaped substantially to conform to the contour of the heel-end portion of the last the operator in the subsequent heel seat lasting operation need only wipe the marginal portions of the upper materials inwardly over the insole and fasten them 55 in lasted position.

Having described the invention, what I claim as new and desire to secure by Letters Patent of the United States is:

1. That method of shaping the heel-end portion of shoe upper materials to the contour of the heel end of a last prior to the heel seat lasting operation which consists in engaging the upper materials frictionally at the opposite sides of the heel end of the last and working them heightwise 70 75

of the last toward its bottom face, and then wiping the same portions of the upper materials heightwise of the last and in the wiping operation applying pressure and heat to said materials 5 to assist in shaping them to the contour of the last.

2. That method of shaping the heel-end portion of shoe upper materials to the contour of the heel end of a last prior to the heel seat lasting 10 operation which consists in wiping the upper materials heightwise of the last toward its bottom face repeatedly while pressing said materials against the opposite side faces of the heel end of the last and in the course of the wiping operation applying heat to said materials to assist in 15 shaping them to the contour of the last.

3. That method of shaping the heel-end portion of shoe upper materials to the contour of the heel end of a last prior to the heel seat lasting 20 operation which consists in pressing the upper materials against the opposite side faces of the heel end of the last and wiping them toward its bottom face without the application of heat thereto, and thereafter again wiping the same 25 portions of the upper materials heightwise of the last while applying heat to said materials.

4. That method of shaping the heel-end portion of shoe upper materials to the contour of the heel end of a last prior to the heel seat lasting 30 operation which consists in pressing the upper materials against the opposite side faces of the heel end of the last and wiping them toward the bottom face of the last without the application of heat thereto, applying a lubricant to the outer 35 layer of the upper materials, and thereafter again wiping the same portion of the upper materials heightwise of the last while applying heat to said materials.

5. That method of shaping the heel-end portion of shoe upper materials to the contour of the heel end of a last prior to the heel seat lasting 40 operation which consists in tensioning the upper materials at the heel end of the last heightwise of the last toward its bottom face by the use of rubber-faced tools, then pressing the upper materials firmly against the opposite side faces of the heel end of the last and wiping them heightwise of the last toward its bottom face by the use of unheated metal-faced tools, and thereafter 45 again wiping the same portions of the upper materials by the use of heated metal-faced tools.

6. In a machine for operating on shoes, the combination with means for supporting a last and shoe having its heel end unlasted, of a plurality 55 of wiping devices, and means for effecting relative movement of said wiping devices and the shoe to wipe the upper at the opposite sides of the heel end of the last repeatedly heightwise of the last toward its bottom face.

60 7. In a machine for operating on shoes, the combination with means for supporting a last and shoe having its heel end unlasted, of a plurality 65 of wiping devices each arranged to engage and press the shoe upper at the opposite sides of the heel end of the last, and means for moving said wiping devices in succession heightwise of the last toward its bottom face.

8. In a machine for operating on shoes, the combination with means for supporting a last 70 and shoe having its heel end unlasted, of an unheated wiping device, a heated wiping device, and means for effecting relative movement of said devices and the shoe to wipe the upper at the opposite sides of the heel end of the last heightwise 75 of the last toward its bottom face.

9. In a machine for operating on shoes, the combination with means for supporting a last and shoe having its heel end unlasted, of a plurality of wiping devices each arranged to engage and press the shoe upper at the opposite sides of the heel end of the last, one of said devices having its upper-engaging faces formed of rubber and another one of said devices having its upper-engaging faces formed of metal, and means for effecting relative movement of said wiping devices and the shoe to wipe the upper repeatedly heightwise of the last toward its bottom face. 5

10. In a machine for operating on shoes, the combination with means for supporting a last and shoe having its heel end unlasted, of a plurality of wiping devices each arranged to engage and press the shoe upper at the opposite sides of the heel end of the last, one of said wiping devices having its upper engaging faces formed of rubber to increase its frictional pull on the 15 upper, and a plurality of carriers for moving said wiping devices in succession heightwise of the last toward its bottom face to wipe the upper. 20

11. In a machine for operating on shoes, the combination with means for supporting a last 25 and shoe having its heel end unlasted, of a plurality of wiping devices each arranged to engage and press the shoe upper at the opposite sides of the heel end of the last, means for moving said wiping devices in succession heightwise of 30 the last toward its bottom face, and means for maintaining one of said wiping devices in a heated condition. 35

12. In a machine for operating on shoes, the combination with means for supporting a last 40 and shoe having its heel end unlasted, of a plurality of wiping devices each arranged to engage and press the shoe upper at the opposite sides of the heel end of the last, means for moving said wiping devices in succession heightwise of 45 the last toward its bottom face, means for maintaining one of said wiping devices in a heated condition, and a device movable with said wiping devices for applying a lubricant to the upper prior to the action of said heated device on the upper. 50

13. In a machine for operating on shoes, the combination with means for supporting a last and shoe having its heel end unlasted, of a plurality of wiping devices each arranged to engage 55 and press the shoe upper at the opposite sides of the heel end of the last, means for moving said wiping devices in succession heightwise of the last toward its bottom face, means for maintaining one of said wiping devices in a heated 60 condition, a device movable with said wiping devices for applying a lubricant to the upper prior to the action of said heated device on the upper, and means for rendering said lubricant-applying device operative or inoperative at will. 65

14. In a machine for operating on shoes, the combination with means for positioning a last and shoe having its heel end unlasted, of a plurality of upper-shaping devices, each comprising a plurality of members arranged to engage and press the upper yieldingly against the opposite side faces of the last, and means for effecting relative movement of said devices and the shoe to wipe the upper repeatedly toward the bottom face of the last. 70

15. In a machine for operating on shoes, the combination with means for positioning a last and shoe having its heel end unlasted, of a plurality of upper-shaping devices movable in succession heightwise of the shoe toward its bottom 75

face to wipe the heel end of the upper, said devices each comprising a plurality of members arranged to engage and press the upper yieldingly against the opposite side faces of the last.

5 16. In a machine for operating on shoes, the combination with means for positioning a last and shoe having its heel end unlasted, of a plurality of upper-shaping devices movable in succession heightwise of the shoe toward its bottom face to wipe the heel end of the upper, said devices each comprising a plurality of members arranged to engage and press the upper yieldingly against the opposite side faces of the last, the upper-engaging members of one of said devices having rubber upper-engaging faces to increase their frictional pull on the upper.

10 17. In a machine for operating on shoes, the combination with means for positioning a last and shoe having its heel end unlasted, of a plurality of upper-shaping devices movable in succession heightwise of the shoe toward its bottom face to wipe the heel end of the upper, said devices each comprising a plurality of upper-engaging members at the opposite sides of the shoe, and separate spring means for forcing each of said upper-engaging members against the shoe.

15 18. In a machine for operating on shoes, the combination with means for supporting a last and shoe having its heel end unlasted, of a plurality of upper-shaping devices each comprising a pair of holders one at each side of the shoe, a plurality of upper-engaging members yieldingly mounted in each of said holders, the upper-engaging members of each device at the opposite sides of the shoe having their upper-engaging faces curved to conform substantially to the opposite edge curvatures of the bottom face of the heel-end portion of the last, and means for moving said devices in succession heightwise of the last to wipe the upper toward the bottom face of the last.

19. In a machine for operating on shoes, the combination with means for supporting a last and shoe having its heel end unlasted, of different devices each comprising a pair of holders one at each side of the shoe, a plurality of upper-engaging members yieldingly mounted in each of said holders, and different pairs of parallel arms for supporting said holders, said arms being rotatable about a common axis extending laterally of the shoe to move said devices in succession heightwise of the shoe to cause said upper-engaging members to press the upper against the opposite side faces of the heel end of the last and to wipe the upper toward the bottom face of the last.

20 20. In a machine for operating on shoes, the combination with means for supporting a last and shoe having its heel end unlasted, of different devices each comprising a pair of holders one at each side of the shoe, a plurality of upper-engaging members yieldingly mounted in each of said holders, different pairs of parallel arms for supporting said holders and for moving them in succession heightwise of the shoe to cause said upper-engaging members to press the upper against the opposite side faces of the heel end of the last and to wipe the upper toward the bottom face of the last, electrical heating units mounted in one of said pairs of parallel arms for maintaining the upper-engaging members of one of said devices in a heated condition, and the upper-engaging members of another one of said devices having their upper-engaging faces formed of felt for applying a lubricant to the upper prior to the action of said heated members on the upper, the parallel arms for supporting the holders of said last-named device being formed in two parts relatively adjustable to render the device operative or inoperative at will.

EUCLID I. LA CHAPELLE.
